UNITED STATES PATENT OFFICE.

EDWARD JABS, OF ELEMWOOD PARK, ILLINOIS.

PRINTING-FRAME.

1,258,118.

Specification of Letters Patent. Patented Mar. 5, 1918.

Application filed February 21, 1917. Serial No. 150,025.

To all whom it may concern:

Be it known that I, EDWARD JABS, a subject of the Emperor of Russia, residing at Elemwood Park, in the county of Cook and 5 State of Illinois, have invented certain new and useful Improvements in Printing-Frames, of which the following is a specification.

My invention relates to printing frames 10 and has for its primary object the provision of improved means for accurately positioning a rubber stamp or similar device with respect to a card, sheet or other printing surface on which an impression is to be 15 made.

A further object of the invention is the provision of an improved stamp guide which shall be yieldable horizontally to permit oscillation of the stamp during the printing 20 action without causing blurring of the impression made upon the card.

A further object of my invention is the provision of guiding means for the card being printed upon and guiding means for the 25 stamp being used, all of which guiding means shall be adjustable as hereinafter described.

Further objects and advantages of the invention will become apparent from the following description taken in conjunction 30 with the accompanying drawings.

In the drawings:

Figure 1 is a top plan view of my invention with a portion broken away to disclose 35 parts below;

Fig. 2 is a front elevation of my invention;

Fig. 3 is a fragmentary side elevation;

Fig. 4 is a section approximately on line 40 4-4 of Fig. 3;

Fig. 5 is a fragmentary section on line 5-5 of Fig. 1;

Fig. 6 is a fragmentary section taken approximately on line 6-6 of Fig. 3.

Reference numeral 10 indicates a base provided with a platen 11 comprising preferably a thick layer of rubber such as is suitable for supporting a card or sheet upon which an impression is to be made from a 45 rubber stamp. The base may be apertured to receive an inking pad 12 operated by means of a handle 13, the pad 12 fitting the base as a drawer fits a table. The platen 11 is preferably square and is contained within 50 a square ridge 14 projecting upward from

the base and having its upper edge flush with the top of the platen. Spanning the platen and in contact with its upper surface is a card guide 15 provided at one end with a finger 16 which depends from the card 60 guide and overlies one reach of ridge 14. A similar finger 17 depends from the opposite end of card guide 15 and overlies the opposite reach of ridge 14. The preferred construction of finger 17 is illustrated in Fig. 65 6 where it will be seen that finger 17 is slightly spaced from ridge 14 and carries a spring 18 which, by means of a set screw 19 threaded into the finger 17 may be cambered into engagement with the outer surface of ridge 14 to secure card guide 15 in 70 engagement with the platen. From this construction it will be seen that card guide 15 may be adjusted horizontally to any position between the front and back of platen 75 11. As seen in Fig. 5 card guide 15 is hollow and provided with a longitudinal slot 21. A card stop 22 is apertured as at 23 to receive the card guide 15 and carries a set screw 24 which traverses the slot 21 and is 80 threaded into a traveling nut 25 fitting the hollow portion of the card guide. The lower surfaces of card guide 15 and card stop 22 lie flush with the upper surface of platen 11. Preferably the stop 22 lies at right 85 angles to the forward surface of card guide 15. Inasmuch as the card guide and the card stop are both adjustable horizontally it will be seen that a card may be positioned with any desired portion of its surface conveniently adjacent to the center of platen 90 11. Positioned directly over card guide 15 and having its forward surface normally aligned therewith is a stamp guide 26 which traverses the platen 11. The mounting for 95 stamp guide 26 comprises a post 27 positioned at one corner of base 10 and carrying an arm 28 which extends preferably to the median line of the platen 11 and at its inner end is T shaped, the T portion 29, Fig. 100 3, of arm 28 being substantially coextensive with stamp guide 26 and card guide 15. The mounting of arm 28 comprises a screw rod 31 swiveled in the upper portion of post 27 and depending into a vertical slot 105 formed in the post, an arm carrier 32 threaded upon rod 31 and a wing nut 33. The carrier 32 overlaps post 27 on opposite sides of its vertical slot. By rotation of rod 31 the elevation of arm 28 may be 110

adjusted and by employing wing nut 33 the carrier 32 may be locked in any vertical adjustment.

The stamp guide 26 comprises preferably 5 a channel shaped bar fitting about the upper and lower surfaces of the T portion 29 of arm 28 and slidably supported thereon by a pair of studs 34, coil springs 35 being interposed between the T and the stamp guide 10 to force the stamp guide normally to the forward limit of movement of studs 34—preferably the studs are fixed in the stamp guide 26 and slidably engage the T 29.

The inner end of arm 28 is pierced to provide 15 a bearing for an adjustable stop rod 36 which parallels the T portion 29 of arm 28 and lies rearwardly thereof in substantially the same horizontal plane. The stop rod is fixed in position in the arm 28 by means of 20 a set screw 37 and carries a stamp stop 38 which is channeled to span stamp guide 26 and may be longitudinally adjusted with respect to the stamp guide. A set screw 39 binds stamp stop 38 in any desired position 25 longitudinally of stop rod 36. As illustrated best in Fig. 3, it will be seen that stamp guide 26 and stamp stop 38 are spaced above platen 11 substantially the same distance. In adjusting the machine for use the 30 card stop 22 and stamp stop 38 are preferably positioned on opposite sides of the center of the arm 28 where it engages its T portion 29.

In the operation of my invention a card, 35 illustrated in dotted lines at 41 in Fig. 1, is laid upon platen 11 with its left-hand end against card stop 22 and its rear edge against card guide 15 the stop and guide operating together to position the card with 40 its edges parallel to stamp guide 26. It being desired to impress the type centrally on card 41 the arm 28 is adjusted forwardly or backwardly to so position stamp guide 26 that, when the side of the rubber stamp is 45 against the stamp guide, the type will be central between the front and back edges of the card. Following this the stamp stop 38 is so adjusted transversely of the platen that a proper spacing of the type between the 50 left and right edges of the positioned card is secured. As is well known, a rubber stamp generally requires oscillation of its handle while the type is in engagement with the card in order that a well inked impression 55 may be left. Were the stamp guide 26 rigidly mounted upon T 29 oscillation of the stamp handle, which would normally be from top to bottom, viewing Fig. 1, that is from back to front, would cause a blurred 60 impression to be left on the card by reason of the fact that the stamp itself would act as a lever, the power applied at the top of the handle being fulcrumed against the face of stamp guide 26 and the type being moved 65 backwardly and forwardly with respect to

the card. In order to prevent such lever action in the stamp I provide the yielding relation between stamp guide 26 and T 29 through the medium of the springs 35. By 70 this means the rolling or oscillating of the rubber stamp merely moves the guide slightly toward and from the T leaving the type stationary with respect to the card 41 and the card stationary in its position against guide 15 and stop 22. The result is 75 a clear impression made by the customary oscillating movement of the handle of the stamp. If desired the stamp stop 38 may be positioned to the left of arm 28, as shown in dotted lines at Fig. 1, and obviously card 80 stop 22 may be positioned at any desired point throughout the length of card guide 15.

While I have illustrated and described the preferred embodiment of my invention it is 85 obvious that one skilled in the art might construct modifications thereof without departing from the spirit of the invention. I wish therefore not to be confined to the precise embodiment shown except in so far as 90 the same is limited in the appended claims.

I claim:

1. The combination with a platen, of card 95 positioning means engaging the upper surface of the platen and adjustable to position the card at any point upon the surface of the platen, and an adjustable stamp guide spaced above said platen and adjacent to the said positioning means.

2. The combination with a platen, of adjustable card positioning means engaging the upper surface thereof, and an adjustable stamp guide mounted above said platen and remote therefrom and adjacent to the card 100 positioning means.

3. In a printing frame the combination 105 with a platen, card positioning means thereon, and an adjustable stamp stop above the platen, of a stamp guide positioned at an angle to said stamp stop and mounted to yield in a direction parallel with the surface 110 of said platen.

4. In a printing frame the combination 115 with a platen, card positioning means upon the same, and an adjustable stamp stop above the platen, of a stamp guide adjustably positioned above the platen and remote therefrom, said guide being parallel to one of the members of said card positioning means and yieldingly mounted to give in a 120 direction parallel to the plane of the platen.

5. In a printing frame the combination 125 with a rectangular base having a ridge about its edges, of a platen contained in said ridge, a card guide spanning said platen, and in contact therewith, a card stop carried by the guide, adjustable longitudinally thereof and in contact with the platen.

6. In a printing frame the combination 130 with a base and a platen carried thereby, of

a card guide traversing said platen and overlapping the edges of said base, one of said overlapping ends carrying a plate of spring metal interposed between said end 5 and the base, and a set screw threaded laterally into said end and bearing against the outer surface of said plate.

7. In a printing frame the combination with a platen, card positioning means and 10 a stamp stop, of an elongated arm spaced above and traversing the platen, and a stamp guide yieldingly mounted upon said arm and movable in a plane parallel to said platen.

15 8. In a printing frame the combination with a platen, card positioning means thereon, and a stamp stop above the platen, of an arm traversing said platen, a stamp guide movably supported by and laterally of said 20 arm and parallel therewith, and springs interposed between said arm and plate.

9. In a printing frame the combination with a platen of an arm spaced above and traversing the platen and having upper and 25 lower horizontal surfaces, a channel shaped stamp guide carried thereby the side webs of which overlap said upper and lower surfaces, studs carried by the guide and slidably engaging apertures provided in the 30 arm, and springs interposed between said arm and guide.

10. A printing frame comprising a platen, a support at one corner thereof, a T shaped arm mounted in said post for vertical adjustment and having an offset shank, the T 35 of said arm traversing said platen, a stop rod adjustably mounted in said arm and paralleling the T thereof, a stamp guide yieldingly carried by the T, and a stamp 40 stop adjustable longitudinally of said rod, overlapping said guide and projecting forwardly of the guide.

11. In a printing frame the combination with a platen having parallel sides, of a card 45 guide traversing the platen in contact there-

with and standing at right angles to said parallel sides, a card stop carried by the card guide, adjustable longitudinally thereof and protruding at right angles thereto, a supporting arm spaced above the platen 50 and traversing the same, a stamp guide paralleling said card guide and yieldable in a plane parallel to the platen, and a stamp stop adjustable longitudinally of said guide and protruding at right angles thereto. 55

12. In a printing frame the combination with a platen having parallel sides of a card guide traversing the platen in contact therewith and standing at right angles to said parallel sides, a card stop carried by the 60 card guide adjustable longitudinally thereof and protruding at right angles thereto, a supporting arm spaced above the platen and traversing the same, a stamp guide paralleling said card guide and yieldable in 65 a plane parallel to the platen, and a stamp stop adjustable longitudinally of said stamp guide and protruding at right angles thereto, said arm being adjustable longitudinally of the parallel sides of said platen. 70

13. In a printing frame the combination with a platen having parallel sides of a card guide traversing the platen in contact therewith and standing at right angles to said parallel sides, a card stop carried by the 75 card guide adjustable longitudinally thereof and protruding at right angles thereto, a supporting arm spaced above the platen and traversing the same, a stamp guide paralleling said card guide and yieldable in a 80 plane parallel to the platen, and a stamp stop adjustable longitudinally of said stamp guide and protruding at right angles thereto, said arm being adjustable longitudinally of the parallel sides of said platen and being 85 adjustable toward and from the platen.

In testimony whereof I have affixed my signature.

EDWARD JABS.
